CLAIM

The ornamental design for a low profile metacarpal fracture brace, substantially as shown and described.

DESCRIPTION

FIG. 1 is a front perspective view of a low profile metacarpal fracture brace, showing our new design;

FIG. 2 is a side elevational view thereof;

FIG. 3 is a side elevational view thereof opposite from the view taken in FIG. 2;

FIG. 4 is an end view thereof;

FIG. 5 is a top plan view thereof; and,

FIG. 6 is a bottom view thereof.

The broken line showing of a hand in FIG. 1 is for illustrative purposes only and forms no part of the claimed design.
